UNITED STATES PATENT OFFICE.

WILLIAM H. SAART, OF ATTLEBORO, MASSACHUSETTS, ASSIGNOR TO THE
JAMES E. BLAKE COMPANY, OF SAME PLACE.

DESIGN FOR A HANDLE FOR BUTTON-HOOKS OR SIMILAR ARTICLES.

SPECIFICATION forming part of Design No. 34,643, dated June 11, 1901.

Application filed May 21, 1901. Serial No. 61,309. Term of patent 3½ years.

To all whom it may concern:

Be it known that I, WILLIAM H. SAART, a citizen of the United States, residing at Attleboro, in the county of Bristol and State of Massachusetts, have invented and produced a new and original Design for the Handle of a Button-Hook or Similar Article, of which the following is a specification, reference being had to the accompanying drawings, forming part thereof.

Figure 1 is a side view of the handle, showing my new design connected with a button-hook, the blade of a paper-knife being indicated in broken lines. Fig. 2 is a sectional view of the handle.

As shown in the drawings, the leading or material feature of my design consists of the raised beads *a a*, extending from the small end to the larger end near the opposite margins in bent and twisted forms resembling

grape-vines, overlayed at intervals by leaf ornaments and inclosing a sunken panel ornamented by a scroll-leafed floral ornament, terminating at the apex of the handle in a tulip-bulb. The ornamentation is repeated 25 on both sides of the handle.

Having thus described my invention, what I claim as new, and desire to secure by Letters Patent, is—

The design for a handle of a button-hook 30 or similar article, as herein shown and described.

In testimony whereof I have signed my name to this specification in the presence of two subscribing witnesses.

WILLIAM H. SAART.
